COFFEE PERCOLATOR

Dominic J. De Fano, Palatine, and Robert I. Kallman,
Elburn, Ill., assignors to Sunbeam Corporation, Chi-
cago, Ill., a corporation of Illinois

Filed Oct. 3, 1966, Ser. No. 4,148

Term of patent 14 years

(Cl. D44—26)

Fig. 3.

Fig. 4.

Fig. 5.

FIG. 1 is a perspective view of a coffee percolator showing our new design;

FIG. 2 is a side elevation view of the coffee percolator;

FIG. 3 is a front elevation view thereof;

FIG. 4 is a rear elevation view thereof; and

FIG. 5 is a top plan view thereof.

The dominant features of the design are shown in solid lines.

We claim:

The ornamental design for a coffee percolator, as shown and described.
